CLAIM

The ornamental design for a fixed blade knife, as shown and described.

DESCRIPTION

FIG. 1 is a perspective view of a fixed blade knife showing my new design;

FIG. 2 is a side elevation view thereof;

FIG. 3 is a top plan view thereof;

FIG. 4 is a bottom plan view thereof;

FIG. 5 is a side elevation view showing an alternative embodiment of the fixed blade knife, the only difference being the length. All other views of the design remain the same.

FIG. 6 is a rear elevation view showing the pommel-end thereof; and,

FIG. 7 is a front elevation view showing the blade-end of the fixed blade knife.

Shading lines shown in the drawings are intended to represent the approximate three-dimensional contour of the design, and are not intended to indicate surface decoration.
